CLAIM

We claim the ornamental design for a “lid,” as shown and described.

DESCRIPTION

FIG. 1 is a perspective view of a lid;

FIG. 2 is a front view of the lid of FIG. 1;

FIG. 3 is a right side view of the lid of FIG. 1;

FIG. 4 is a left side view of the lid of FIG. 1;

FIG. 5 is a back view of the lid of FIG. 1;

FIG. 6 is a top view of the lid of FIG. 1;

FIG. 7 is a bottom view of the lid of FIG. 1;

FIG. 8 is a perspective view of the lid of FIG. 1;

FIG. 9 is a bottom perspective view of the lid of FIG. 1;

FIG. 10 is a top perspective view of the lid of FIG. 1 in an open configuration; and,

FIG. 11 is a top perspective view of a lid of FIG. 1 in an open configuration.

Broken lines depict portions of the lid and form no part of the claimed design.
